UNITED STATES PATENT OFFICE.

GROVER C. GREENE, THOMAS OSCAR TUNE, AND ROBERT E. STAMPS, OF NASHVILLE,
TENNESSEE.

SELF-SERVING STORE.

Application filed August 4, 1921. Serial No. 489,797.

To all whom it may concern:

Be it known that we, GROVER C. GREENE, THOMAS O. TUNE, and ROBERT E. STAMPS, citizens of the United States, residing at 5 Nashville, in the county of Davidson and State of Tennessee, have invented certain new and useful Improvements in Self-Serving Stores, of which the following is a specification.

10 This invention relates to improvements in self serving stores and has as its general object to provide a novel arrangement of store fixtures such that customers may more conveniently serve themselves and with little 15 likelihood of confusion or congestion in the aisles of the storeroom.

Another object of the invention is to provide in a self serving store, a novel arrangement of the checking or cashier's station 20 such as to admit of a better display of the goods on sale to the view of a customer passing or entering the store and thus enable the tradesman to attract trade.

Another object of the invention is to provide 25 an arrangement such that customers entering the store may to a certain extent gain an idea of the nature of the articles carried in stock and the prices thereof before actually entering the enclosures wherein the 30 selections are to be made so that it is likely that a customer will determine what articles are desired before actually reaching the display shelves or cases where the articles are stored or placed on sale.

35 In the accompanying drawings:

Figure 1 is a plan view of the store arrangement embodying the invention;

Figure 2 is a vertical front to rear sectional view on the line 2—2 of Figure 1 looking in the direction indicated by the arrows;

Figure 3 is a vertical transverse sectional view on the line 3—3 looking in the direction indicated by the arrows.

In the drawings, the numeral 1 indicates 45 in general the storeroom within which various fixtures are arranged in accordance with the present invention, and the storeroom is bounded by side walls 2 and 3, a rear wall 4, and a front 5, the latter being preferably provided with display windows 6 and a doorway 7 through which the customers may enter, this doorway being closed by doors 8 of any desired type.

55 Tiers of shelves, showcases, cabinets, or other fixtures of like nature for the storage

and display of articles of merchandise are arranged along the walls 2, 3 and 4 of the storeroom and are indicated respectively by the numerals 9, 10 and 11. The fixtures 9 preferably extend the entire length of the 60 wall 2 as do also the fixtures 11 with regard to the wall 4, but the fixtures 10 extend from the rear end of the wall 3 to a point spaced from the store front 5, as best shown in Figure 1 of the drawing, and for the 65 purpose of providing a lobby at the front of the storeroom at one side of the doorway 7, this lobby being indicated by the numeral 12 and being furnished with any suitable fixtures such for example as a bench or 70 table 13.

The numeral 14 indicates in general a checking and cashier's station which is preferably in the nature of a rectangular enclosure or counter located substantially midway between the side walls 2 and 3 of the storeroom and suitably spaced from the rear wall 4 and fixtures 11 to provide a passageway 15 between it and the said fixtures. A basket rack 16 is preferably provided at 80 that side of the checking station counter which is located next adjacent the wall 2, and a cash register and various other fixtures peculiar to the duties to be performed by the attendant at the station, and indicated by the numeral 17, are provided upon the counter 14. The numeral 18 indicates a railing which extends longitudinally of the storeroom from that side of the doorway 7 which is adjacent the fixture 9, and parallel 85 to said fixtures, and to a point suitably spaced in front of the checking station 14, a passageway 19 being provided between the rear end of the rail 18 and the front of the checking station counter. Shelving or other 90 similar fixtures, indicated by the numeral 20, is arranged within the storeroom between the railing 18 and the fixtures 9 and parallel to the two and this shelving extends from a point spaced from the store front 5 to a 10 point terminating slightly forwardly of the rear end of the railing 18 so that between the shelving 20 and railing 18 there is provided a passageway 21; between the forward end of the shelving and the store front a 11 passageway 22; and, between the shelving and the fixtures 9, a passageway 23. A railing 24 extends longitudinally of the storeroom from a point opposite the rear end of the railing 18, in a forward direction to a 1

point opposite or slightly in advance of the forward end of the fixtures 10, where it is turned laterally and extends across the storeroom to the wall 3 and defines one boundary 5 of the lobby 12, the forward portion of the railing 18, the wall 3, and the store front 5, constituting the other boundaries of the said lobby. Shelving or other fixtures 26 is arranged within the storeroom to extend longitudinally thereof between and parallel to the railing 24 and fixtures 10 and this shelving extends from a point terminating short of the laterally curved portion 25 of the railing 24 to a point suitably spaced in advance 10 of the rear end of the railing 24. Thus there is provided a passageway 27 between the shelving 26 and fixtures 10; a passageway 28 between the forward end of the shelving 26 and the portion 25 of the railing 24; and, a passageway 29 between the shelving 26 and the railing 24.

The railings 18 and 24 provide between them a combined entrance and exit passageway 30 which extends longitudinally of the 25 storeroom from the lobby 12 to the front of the checking station 14. The numeral 31 indicates in general a rearward continuation of the railing 24, this continuation being first extended laterally, as at 32, from 30 the rear end of the railing 24 and thence rearwardly, as at 33, parallel and adjacent to one side of the checking station counter 14, as indicated by the numeral 34, and terminating at its rear end at a point spaced 35 from the fixtures 11. Thus the extension 34 defines between it and the checking station 14 a passageway 34 and between its rear end and the fixtures 11 a passageway 35. Also there is a passageway 36 provided 40 between the portion 33 of the extension 31 and the fixtures 10.

A partition railing 37 extends forwardly from the back of the checking station counter 14 and between the railings 18 and 24, as 45 best shown in Figure 1 of the drawings, and defines entrance and exit passageways 38 and 39 respectively which are closed by a turn stile 40 except that by passing this stile persons may enter the enclosed portion 50 of the storeroom by way of the passage 38 and leave the same by way of the passage 39. In the first instance they pass the basket rack 16 from which they may select baskets or other containers for their purchases, and 55 after making this selection pass along the passageways 21, 22, 23, 15, 35, 27, 28, 24 and 36, and again by the passageway 35 to the passageway 34 and finally out through the exit passageway 39, previous to which their 60 selections are checked and paid for at the checking station 14.

It will be evident and particularly by reference to Figure 1 that the checking station is located at the rear of the storeroom 65 so that practically the entire front portion

of the storeroom is devoted to the display of the articles of merchandise on sale, and prospective customers, before entering the enclosures within the storeroom, can pass along the passageway 30 and while doing so 70 may view the goods displayed upon the shelves 20 and 26 with the result that to an extent at least they determine in their minds what purchases they intend to make before entering the enclosure defined by the railings 75 18 and 24 and having made their decisions, there is less likelihood of congestion, and the service is expedited. Another advantage gained by locating the checking station at the rear of the storeroom rather than at 80 the front as has heretofore been customary, lies in the fact that a store manager or other attendant in charge stationed at the counter 14 may better observe the conduct of customers and guard against theft or improper 85 handling of the articles of merchandise on sale.

Having thus described the invention, what is claimed as new is:

1. In a self-serving store, a sales room 90 having an entrance, an aisle extending from the entrance to a relatively remote point and substantially midway longitudinally between the side walls of the room, a checking station arranged opposite the end of 95 the aisle and in spaced relation thereto, means dividing the aisle longitudinally at its said end and extending from the checking station toward the entrance a distance into said aisle whereby to define distinct 100 entrance and exit passageways, means controlling the passage of customers through the said passageways, article storage means extending longitudinally within the space at either side of the aisle and parallel thereto and to the respective wall of the room 105 whereby to display the articles stored thereby to customers passing through the aisle and before their entry through the entry passageway, the said storage means defining a circuitous passageway at either side of the aisle and means extending from one side of the rear end of the aisle laterally and thence rearwardly and past one side of the checking station in spaced relation thereto to define an exit passageway through 110 which customers must pass in leaving the sales room.

2. In a self-serving store, a sales room having an entrance, an aisle extending from the entrance to a relatively remote point and substantially midway longitudinally between the side walls of the room, a checking station arranged opposite the end of the aisle and in spaced relation thereto, means 120 dividing the aisle longitudinally at its said end and extending from the checking station toward the entrance a distance into said aisle whereby to define distinct entrance and exit passageways, means con- 125

trolling the passage of customers through the said passageways, and article storage means extending longitudinally within the space at either side of the aisle parallel thereto and to the respective wall of the room, the entrance and exit passageways being located rearwardly within the room beyond the rear ends of the article storage means whereby articles stored by said means will be displayed to customers passing ¹⁰ through the aisle and before their entry through the entry passageway.

In testimony whereof we affix our signatures.
